DESCRIPTION

U.S. PATENT DOCUMENTS

FIG. 1 is a first perspective view of a rack mount kit for desktop network appliances showing our new design thereof;

D1,008,243 S * 12/2023 Cantineau D14/447
D1,008,244 S * 12/2023 Cantineau D14/447
D1,008,245 S * 12/2023 Cantineau D14/447
D1,008,246 S * 12/2023 Cantineau D14/447
D1,008,247 S * 12/2023 Cantineau D14/447
D1,008,248 S * 12/2023 Cantineau D14/447
D1,008,249 S * 12/2023 Cantineau D14/447
D1,008,250 S * 12/2023 Cantineau D14/447

FIG. 2 is a second perspective view thereof;

FIG. 3 is a front view thereof;

FIG. 4 is a back view thereof;

FIG. 5 is a top view thereof;

FIG. 6 is a bottom view thereof;

FIG. 7 is a first side view thereof; and,

FIG. 8 is a second side view thereof.

The broken lines depict portions of the rack mount kit for network appliances that form no part of the claimed design.
